LEATHER JACKET

Filed Sept. 1, 1931

INVENTOR

Stanford Raymond
BY *R. J. DeWolfe*
ATTORNEY

UNITED STATES PATENT OFFICE

STANFORD RAYMOND, OF STOCKTON, CALIFORNIA

DESIGN FOR A LEATHER JACKET

Application filed September 1, 1931. Serial No. 40,976. Term of patent 3½ years.

To all whom it may concern:

Be it known that I, STANFORD RAYMOND, a citizen of the United States, residing at Stockton, in the county of San Joaquin and State of California, have invented a new, original, and ornamental Design for Leather Jackets, of which the following is a specification, reference being had to the accompanying drawing, forming part thereof.

The figure is a plan view of a leather jacket, showing my new design. The opposite side of the design is substantially plain and unornamented.

The distinctive feature of the design is the slanting pocket openings, and the provision of lines of stitching, outlining the pockets, and clearly visible on the front of the jacket, extending from the ends of the pocket openings toward each other to define, with said pocket openings, a symmetric pentagonal area.

I claim:

The ornamental design for a leather jacket, as shown and described.

STANFORD RAYMOND.
